PROCESS FOR PREPARING LUBRICATING OILS

Vanderveer Voorhees, Hammond, Ind., assignor to Standard Oil Company, Chicago, Ill., a corporation of Indiana

Application December 14, 1934, Serial No. 757,439

11 Claims. (CL 196—13)

This invention relates to processes of extracting hydrocarbon oils with selective solvents and it pertains more particularly to a process whereby certain parts of the extract and raffinate are recycled to aid in the extraction of the oil.

Petroleum is essentially a mixture of hydrocarbons comprising groups of homologous series of compounds such as the paraffins, hydro aromatics, aromatics, high molecular weight polymethylenes, derivatives of all of these classes, and various other series in which the hydrogen to carbon ratio is even lower than in the above classes. A large number of individual compounds of each series are present in the oil but have different boiling points, physical and chemical properties.

In the various types of crude petroleums commonly known as paraffin base, naphthene or asphalt base and mixed base oils, these various series of hydrocarbons are present in different proportions. For example, in the paraffin base oils such as those from the Appalachian field, there is a relatively high proportion of paraffinic hydrocarbons having chain structures and high hydrogen to carbon ratios, whereas in the Gulf Coastal oils there is a high proportion of hydrocarbons with ring structures and low hydrogen to carbon ratio. The mixed base oils such as those from Oklahoma and Mid-Continent areas are in general intermediate these two extreme types of oil.

In the normal refining of crude petroleum, the fractions of varying distillation ranges, which are successively obtained by distillation of the oils, partake of the general character of the crude; for example, the heavy lubricating oil distillates derived from Appalachian crudes will show paraffinic characteristics, whereas the heavy distillates derived from Winkler crude show naphthenic characteristics. The distillates from the mixed base crudes, such as those from the Mid-Continent area, will show characteristics common to both the paraffinic and naphthenic oils. An important property of paraffinic lubricating oils is their low viscosity temperature coefficients or rates of change of viscosity with temperature. In other words, these oils have high viscosity indices. This property makes them particularly suitable for certain lubrication problems where high temperatures are encountered. At low temperatures also, these oils retain their fluidity better, an important consideration in cold weather. For this reason, it is very desirable to separate from lubricating oils and from the mixed base oils in particular the undesirable naphthenic and aromatic constituents (compounds tending to

form sludge) thereby making the oil more paraffinic. Various methods have been proposed for doing this and some have been used with partial success; thus, the oil may be subjected to vigorous treatment with sulfuric acid followed by neutralization and removal of harmful sulfuric acid derivatives.

The expression "viscosity index", as used herein, refers specifically to the index of lubricating oils, defined by Dean and Davis in Chemical and Metallurgical Engineering, volume 36, page 618, 1929. The viscosity index of a lubricating oil is an indication of its composition or type, that is, whether it is a paraffin base or naphthene base oil. Paraffin base oils are arbitrarily assigned a viscosity index of 100, naphthene base oils are assigned a viscosity index of zero, and mixed base oils lie between these extremes. By the present invention I have made it possible to obtain from mineral oils containing a mixture of paraffinic and naphthenic compounds, a maximum yield of paraffin type hydrocarbons (with a high viscosity index) with the minimum amount of solvent and without the nuisance or cost of acid treating and without appreciable destruction of the naphthenic constituents of the oil.

The term "naphthenic hydrocarbons" is employed in this application and in the claims in a generic sense to include the hydrocarbons that are aromatic, aromatic-like, and olefinic in composition as well as the polymethylene hydrocarbons. The above naphthenic compounds found in lubricating oils are responsible for the low viscosity indices and sludge-forming properties of these oils, whereas in the case of the low-boiling oils, such as naphthas and cracked naphthas, the naphthenic compounds are responsible for the anti-detonating characteristics of these distillates. In all crudes, the hydrocarbons in the lubricating oil range are mixtures in which all shades of naphthenicity and paraffinicity are represented to a greater or lesser extent, depending on the type of crude. There is accordingly a fairly continuous distribution of hydrocarbons of low, intermediate and high viscosity index, making separation much more difficult than would be the case if the oils contained only two or three types of hydrocarbons.

An object of my invention is to produce an improved method for the continuous countercurrent extraction of mineral oils so that I can obtain a lubricating oil raffinate which has a high viscosity index or is highly paraffinic and stable against sludge formation, and a second fraction,

the extract, which has a low viscosity index or which is highly naphthenic or aromatic in composition.

A particular object of my invention is to provide a process for extracting mineral oils whereby a certain part of the raffinate and/or extract can be used in combination with a solvent to extract the oil; thereby reducing the amount of solvent normally used to extract the oil. My invention is illustrated by Figures 1 and 2, which form a part of this specification.

Figure 1 is a diagrammatic elevation of an apparatus for the extraction of oils by my improved process.

Briefly, the general outline of my new process is as follows: A mineral lubricating oil containing paraffinic and naphthenic constituents is given a countercurrent extraction with a suitable solvent, the raffinate and extract fractions are cooled and removed to separate chambers and permitted to separate or settle into layers. Part of the most naphthenic extract is returned to the extractor to aid in the further extraction of fresh oil. Likewise, a part of the most paraffinic raffinate is returned to the extractor to aid in the further extraction of fresh oil. Either or both of these steps may be used.

The oil to be extracted, for example a mixed base mineral oil distillate having a gravity of 26.6 A. P. I., a Saybolt viscosity of 114 seconds at 210° F. and a viscosity index of about 56, is forced by pump 10 through conduit 11 and introduced into vertical extractor 12 at a point slightly below or at about the middle thereof by perforated pipe 13. Before starting the process, extractor 12 may be filled with the oil or solvent and in this example I will assume that extractor 12 is filled with solvent as the continuous phase. The oil, being lighter than the solvent, passes up through the solvent which is continuously introduced into the top part of the tower through perforated pipe 14. The solvent descends through the tower and thereby effects a countercurrent extraction of the ascending oil. Any suitable means, such as pump 15 and conduit 16, may be used to pass the solvent into perforated pipe 14. The oil and/or solvent may be heated before being introduced into the extractor so that the extraction will be effected at the desired temperature. The extractor may also be heated and/or cooled at various points by coils or jackets (not shown). When a solvent like di(2-chlorethyl)ether is used, the extraction is suitably carried out at a temperature ranging from 75 to 125° F. When a solvent like cresylic acid is used, the extraction temperature may range from 125 to 175° F. Higher or lower temperatures may be used to suit the particular type of oil and solvent and to conform with the practice of the refiner. The volume of solvent used may vary over a wide range, but due to my particular method of extracting, good yields of high viscosity index oils can be produced with small quantities of solvent, for example 0.5 to 1.5 volumes of solvent for each volume of oil. The process may also be operated with somewhat larger volumes of solvent, for example 1.5 to 3 volumes of solvent may be used for each volume of oil. Selective solvents such as phenol, nitrobenzene, furfural, chloraniline or mixtures of any of these may be used. Previous to extraction the oil may be refined by any of the usual refining agents such as sulfuric acid, aluminum chloride, fuller's earth, propane, etc.

The solvent, with the dissolved extract or low viscosity index constituents, is withdrawn from

the bottom part of extractor 12 through conduit 17 and passed to cooler 18 where it is cooled to a temperature ranging from 25 to 80° F. below the temperature of extraction and thence through conduit 19 to extract separator 20. The manner of using a part of this extract in the further extraction of the oil in extractor 12 will be described hereinafter.

The raffinate comprising the highly paraffinic constituents is withdrawn from the top part of the extractor through conduit 21 and passed to cooler 22 where it is cooled to a temperature from 25 to 80° F. below the temperature of extraction and thence through conduit 23 to raffinate separator 24. A small amount of solvent will be present in the raffinate. The use of a portion of this raffinate in the further extraction of the oil in extractor 12 will be described hereinafter.

The admixture of solvent and extract in separator 20 separates into two layers hereinafter referred to as "extract #1" and "extract #2". The former collects in the upper part of separator 20 and the latter collects in the lower part of the separator. Extract #2 is composed of a part of the solvent and the most highly naphthenic constituents or the constituents having the lowest viscosity index. Extract #1 is composed of a part of the solvent and the less naphthenic constituents which have a somewhat higher viscosity index than the constituents of extract #2.

Likewise, the raffinate separates into two fractions hereinafter referred to as "raffinate #2" and "raffinate #1". The former collects in the upper part of the separator 24 and the latter collects in the lower part of the separator. Raffinate #2 is composed of a small part of the solvent and the most paraffinic constituents of the oil or the constituents having the highest viscosity index. Raffinate #1 is composed of a small part of the solvent and the less paraffinic constituents which have a somewhat lower viscosity index than the constituents in raffinate #2. If desired, several separators like 20 and 24 may be used in parallel to effect a separation of the extract and raffinate into fractions.

A portion of extract #2 containing the very low viscosity index constituents is withdrawn from separator 20 and forced by pump 25 through valved conduit 26 to the top part of the extractor and introduced therein through perforated conduit 27 at a point slightly below solvent inlet pipe 14. The highly naphthenic or low viscosity index constituents in the extract, being miscible with the solvent, promote contact between the solvent and the oil in the top part of the extractor, but being easily extracted by the solvent they are prevented from escaping from the top of the extractor with the raffinate in line 21. The added naphthenic constituents and solvent descend through the extractor 12 and effect a countercurrent extraction of the ascending oil. In effect, these added naphthenic constituents take the place of a part of the solvent and thereby reduce the quantity of the particular solvent normally used in the extraction of oils, and permit the use of more hydrophylic solvents such as the alcohols, ketones, sulfur dioxide, etc.

Likewise, part of raffinate #2 containing the higher viscosity index constituents, is withdrawn from the top part of raffinate separator 24 and forced by pump 28 through valved conduit 29 to perforated pipe 30 in the lower part of tower 12. This paraffinic raffinate, being only slightly miscible with the oil solution in the lowermost part

of the tower, forms a separate phase which rises through the tower and serves to absorb or extract from the solution therein, those constituents of intermediate viscosity index desired in the raffinate.

It should be understood that the extract removed by conduits 31 and 32 and the raffinate removed by conduits 33 and 34 may be distilled or given any conventional treatment to recover the solvent from the oil. The recovered solvent is recycled through conduit 16. The conduits 30 and 35 should be spaced far enough above the lower end of the extracting tower 12 so that a quiescent zone may exist in the lower part of said tower. The same precaution should be followed with respect to conduits 14 and 27. Baffles may be placed in either or both of these quiescent zones to prevent a turbulent action.

In the accompanying diagram, Figure 2, I have shown a theoretical distribution of viscosity index throughout the lubricating oil range. Although this diagram is not based on actual data it is believed to be approximately correct in view of related data and observations on the behavior 25 of lubricating oils partially separated into their constituents by selective solvents.

The diagram represents a typical lubricating oil distillate from mixed base crude and is believed to show the results which would be obtained by separating this oil into small fractions 30 on the basis of viscosity index, i. e., each fraction to be homogeneous or substantially homogeneous from the standpoint of the viscosity index of its constituents. In the separation of oils to 35 prove the viscosity index, the maximum yield and/or viscosity index would be obtained by sharply separating the mixture between two hydrocarbon constituents, rejecting all hydrocarbons of lower viscosity index. This is not practicable commercially but is the aim in all commercial processes of this kind. It is illustrated 40 in the chart by intersecting the area under the curve with the line *a*—*b*, all hydrocarbons lying to the right being of higher viscosity index than any of those on the left of the line *a*—*b*.

It may be observed from this theoretical diagram that it would be very difficult to separate two oils whose viscosity indices are close together because the chemical and physical differences in 50 that case are very slight. Referring to the chart, the letter "a" designates a fraction of about 55 viscosity index while the letters "c" and "d" designate fractions of about 15 and 92 viscosity index, respectively. Although it is very difficult to 55 separate the mixture sharply into oils having viscosity indices slightly above and below that represented by the point "a", it would be relatively easy to separate oils lying above (to the right of) the point "d" and below (to the left of) the point "c" were they alone in the mixture.

In the drawings, E represents the most naphthenic material (to the left of point *c*), F represents intermediate naphthenic material (between points *a* and *c*), G represents intermediate paraffinic material (between points *a* and *d*), and H represents the most paraffinic material (to the right of point *d*). Let us assume that E and F are to be separated from G and H. A large amount of F, being intimately associated with G, is carried into the raffinate end of the system. In practicing my invention I introduce E into this raffinate end because it is so naphthenic that it is immiscible with the good oil leaving that part of the system and at the same time it is 70 relatively miscible with F and it therefore has

the effect of extracting F from the raffinate and returning it to the extract. It should be noted that I am not recycling that portion of the extract which contains desirable paraffinic material for the purpose of recovering such material;—I am returning the most naphthenic material to the raffinate end of the system because I have found that it is least likely to contaminate the raffinate and at the same time is most effective in modifying the solvent and in combining 10 with the intermediate naphthenic components, carrying said components to the extract end of the system.

Similarly, a considerable portion of intermediate paraffinic material G may find its way into 15 the extract end of a solvent extraction system. In order to prevent the loss of this material with the extract, I recycle part of the most highly paraffinic material H to the extract end of the tower. This material H is so dissimilar to E 20 that it is immiscible therewith in the presence of the solvent and therefore it is not carried away with the extract. At the same time this material H, more closely resembling G, becomes intimately associated with G and carries it back 25 to the raffinate end of the extraction system. Here again it should be noted that I am not returning an insufficiently extracted paraffinic fraction for further extraction,—I am returning the most paraffinic fraction to the extract end of the 30 system for preventing the loss of fractions of intermediate paraffinity. My invention contemplates either the recycling of highly paraffinic raffinate to the extract end of the system or the recycling of highly naphthenic extract to the 35 raffinate end of the system or both.

Referring again to Figure 1, I may employ more effective fractionating means for separating extract #1 from extract #2 and raffinate #1 from raffinate #2. In place of separators 20 40 and 24, for example, I may use countercurrent towers with progressive cooling and recycling. I may also employ an additional solvent, for example, light naphtha, hexane, butane or propane for improving the separation. I may likewise 45 introduce hexane or propane into the base of extractor 12 through the perforated conduit 35 to assist in removing paraffinic material which may be mechanically or otherwise carried out of the extractor with the extract. The volume of 50 propane, butane, hexane, or light hydrocarbon fraction may vary over a wide range, depending upon the oil and solvent used, but 0.1 to 0.5 volume of such solvents may be employed for each volume of oil extracted. Such additional 55 solvent may be recovered by distillation from the extract fractions, and, of course, the principal solvent may be recovered and recirculated by pump 15.

While I have described this invention in relation to a particular application thereof, I intend that it shall be limited only by the following claims:

1. The method of refining a hydrocarbon oil containing a plurality of components of varying 65 degrees of paraffinity and naphthenicity which comprises countercurrently extracting said oil with a selective solvent to give a raffinate and an extract, separating the raffinate into highly paraffinic and less paraffinic fractions, and returning the highly paraffinic fraction to the countercurrent extraction system for recovering less paraffinic materials which would otherwise be lost 70 in the extract.

2. The method of refining a hydrocarbon oil 75

containing a plurality of components of varying degrees of paraffinicity and naphthenicity which comprises countercurrently extracting said oil with a selective solvent to give a raffinate and an extract, separating the raffinate into highly paraffinic and less paraffinic fractions, and returning the highly paraffinic fraction to the extract end of the countercurrent extraction system for recovering less paraffinic materials which would otherwise be lost in the extract.

3. In a continuous process for separating mineral lubricating oils containing paraffinic and naphthenic constituents into a raffinate fraction of highly paraffinic constituents and an extract fraction of highly naphthenic constituents, the steps comprising countercurrently extracting the oil in an elongated vertical extracting zone with a selective solvent whereby there are obtained a raffinate fraction and an extract fraction, removing said extract fraction and raffinate fraction to separate zones, separating said raffinate fraction further into a more paraffinic and a less paraffinic fraction, returning to a point near the extract end of the extracting zone a part of the more paraffinic fraction and permitting it to pass countercurrently through said extracting zone whereby it supplements the countercurrent extraction of the oil by the selective solvent.

4. Steps according to claim 3 in which said separating step is accomplished by cooling said raffinate fraction about 25 to 80° F.

5. In the process of separating a mixture of mineral lubricating oil hydrocarbons into fractions of low viscosity index and high viscosity index, the steps comprising countercurrently extracting the low viscosity index hydrocarbons from said mixture by means of a suitable selective solvent whereby they are obtained a raffinate fraction of relatively high viscosity index and an extract fraction of relatively low viscosity index, separating said raffinate fraction further into a more paraffinic and a less paraffinic fraction, separating said extract fraction further into a more naphthenic and a less naphthenic fraction, and returning to the initial countercurrent extraction operation a part of the more naphthenic extract fraction and a part of the more paraffinic raffinate fraction.

6. In the process of separating a mixture of lubricating oil hydrocarbons containing a large number of hydrocarbons of different viscosity index distributed continuously throughout the composition range of said mixture, the steps comprising separating said mixture by extraction into four fractions according to viscosity index and employing the most paraffinic fraction as an agent for absorbing hydrocarbons of intermediate viscosity index in one part of the extraction system and employing the most naphthenic fraction for absorbing naphthenic hydrocarbons in another part of the extraction system.

7. In a continuous process for separating mineral lubricating oils containing paraffinic and naphthenic constituents into a raffinate fraction of highly paraffinic constituents and an extract fraction of highly naphthenic constituents, the steps comprising countercurrently extracting the oil in an elongated vertical extracting zone with a selective solvent whereby there are obtained a raffinate fraction and an extract fraction, removing said extract fraction and raffinate fraction to separate zones, separating said raffinate fraction further into a more paraffinic and a less paraffinic fraction,

affinic fraction, separating said extract fraction further into a more naphthenic and a less naphthenic fraction, returning to the raffinate end of the extracting zone a part of the more naphthenic fraction, returning to the extract end of the extracting zone a part of the more paraffinic fraction and permitting the more paraffinic and more naphthenic fractions to pass countercurrently through said extracting zone whereby they supplement the countercurrent extraction of the oil by the selective solvent.

8. In a process for separating mineral lubricating oils containing paraffinic and naphthenic constituents into a raffinate fraction of highly paraffinic constituents and an extract fraction of highly naphthenic constituents, the steps comprising countercurrently extracting the oil in an elongated extracting zone with a selective organic solvent whereby there are obtained a raffinate fraction and an extract fraction, removing said extract fraction and raffinate fraction to separate zones, separating said raffinate fraction further into a more paraffinic and a less paraffinic fraction, separating said extract fraction further into a more naphthenic and a less naphthenic fraction, returning to a point near one end of the extraction zone a part of the more naphthenic fraction, returning to the other end of the extracting zone a part of the more paraffinic fraction and permitting the more paraffinic and more naphthenic fractions to pass countercurrently through said extracting zone whereby they supplement the countercurrent extraction of the oil by the selective solvent.

9. Steps according to claim 8 in which said separating steps are accomplished by separately cooling said fractions about 25 to 80° F.

10. In the process of separating mineral lubricating oils containing paraffinic and naphthenic constituents into a raffinate fraction of highly paraffinic constituents and an extract fraction of highly naphthenic constituents, the steps comprising countercurrently extracting the oil in an elongated vertical extracting zone with a selective solvent and propane, said selective solvent being introduced into the upper part of the extracting zone and said propane being introduced into the lower part of said extracting zone, whereby there are obtained a raffinate fraction and an extract fraction, removing said extract fraction and raffinate fraction from the extracting zone, cooling these fractions to temperatures from about 25 to 80° F. below the temperature used in the extracting zone, passing said cooled extract fraction and raffinate fraction to separate zones, permitting said raffinate fraction to separate further into a more paraffinic and a less paraffinic fraction, permitting said extract fraction to separate further into a more naphthenic and a less naphthenic fraction, returning to the upper part of the extraction zone a part of the more naphthenic fraction, returning to the lower part of the extraction zone a part of the more paraffinic fraction, and permitting the more naphthenic and more paraffinic fractions to pass countercurrently through said extracting zone whereby they supplement the countercurrent extraction of the oil by the selective solvent and propane.

11. The process as described in claim 10 wherein a low boiling paraffinic hydrocarbon is used in the place of propane.

CERTIFICATE OF CORRECTION.

Patent No. 2,079,885.

May 11, 1937.

VANDERVEER VOORHEES.

It is hereby certified that error appears in the printed specification of the above numbered patent requiring correction as follows: Page 1, first column, line 3, for "whereby" read wherein; page 4, second column, line 28, claim 8, after "to" insert the words a point near; and line 51, claim 10, for "raffiate" read raffinate; and that the said Letters Patent should be read with these corrections therein that the same may conform to the record of the case in the Patent Office.

Signed and sealed this 29th day of June, A. D. 1937.

Henry Van Arsdale

Acting Commissioner of Patents.
